UNITED STATES PATENT OFFICE.

EDGAR A. GAY, OF ROCHESTER, NEW YORK.

DESIGN FOR STOCK-BEADING FOR TRIMMING FURNITURE, &c.

SPECIFICATION forming part of Design No. 32,439, dated April 3, 1900.

Application filed February 14, 1900. Serial No. 5,226. Term of patent 7 years.

To all whom it may concern:

Be it known that I, EDGAR A. GAY, a citizen of the United States, residing in the city of Rochester, county of Monroe, and State of New York, have invented and produced a new and original Design for Stock-Beading for Trimming Furniture, &c., of which the following is a specification, reference being had to the accompanying figures of the drawings, forming a part thereof, of which—

Figure 1 is a plan view, Fig. 2 a side elevation, and Fig. 3 a perspective view, of the beading.

The leading feature of my design consists of the shape and configuration of the beading, which embodies a series of approximately hemispherical or dome shaped beads A, ar-

ranged side by side and connected by a short band or rib B, extending between their proximate edges. Slight depressions b are formed in the tops of the beads A, from the center of which rise smaller beads a, resembling pin-heads, and some of the said depressed portions are provided with apertures c.

Having described my design, what I claim as new, and desire to secure by Letters Patent, is—

The design for a stock-beading, substantially as herein shown and described.

EDGAR A. GAY.
